UNITED STATES PATENT OFFICE.

LAURENCE EDWIN STEWART, OF BRADFORD, PENNSYLVANIA, ASSIGNOR TO CONSOLIDATED MACHINE COMPANY, OF BRADFORD, PENNSYLVANIA.

APPARATUS FOR DRAWING GLASS CYLINDERS.

1,347,131.

Specification of Letters Patent.

Patented July 20, 1920.

Application filed August 8, 1919. Serial No. 316,148.

To all whom it may concern:

Be it known that I, LAURENCE E. STEWART, a citizen of the United States, and a resident of Bradford, in the county of Mc-
5 Kean and State of Pennsylvania, have invented certain new and useful Improvements in Apparatus for Drawing Glass Cylinders; and I do hereby declare the following to be a full, clear, and exact description of the invention, such as will enable others skilled in the art to which it appertains to make and use the same.

My invention relates to an improvement in apparatus for drawing glass cylinders and particularly to means for gradually increasing the pressure of air for holding the cylinder distended as the draw progresses, and it consists in the parts and combination of parts as will be more fully explained and 20 pointed out in the claims.

In the accompanying drawings; Figure 1 is a diagrammatic view of circuits and controlling devices for use in a cylinder drawing apparatus; Fig. 2 is a view showing the 25 bait hoist and the automatic rheostat mechanically connected with the same; Fig. 3 is a view showing the cage 5 carrying the fan and its motor and also the bait tube and bait, and Fig. 4 is a view in plan of a portion 30 of the mechanism shown in Fig. 2.

This invention is designed for use with a drawing apparatus wherein a blower fan 5^a for supplying air to the interior of the cylinder is carried in a cage 5 which carries 35 the drawing bait, and which also carries an electric motor 5^b for actuating the blower or fan. This cage 5 is suspended from a hoist cable 6 and carries the pipe 7 having the bait 8 at the lower end thereof. The fan 40 5^a and motor 5^b are located in the cage 5, and the motor is connected in circuit and controlled as hereinafter explained.

The cable 6 for lifting and lowering the cage 5 is attached to the hoisting drum 14 45 at one end of the shaft 15 which is mounted in a bearing 16. Secured to the end of a shaft 15, so as to rotate therewith is the worm 17 which is in mesh with the worm wheel 18 secured on shaft 19, the latter

being mounted in bearings at the upper ends 50 of brackets 20, carried by the I-beam frame of the hoisting engine. Shaft 19 carries a sprocket wheel 21 which is connected with sprocket wheel 22 on the shaft 23 of the automatic rheostat 24, by the sprocket chain 55 25, so that said shaft, which carries the movable contact arm 26 rotates or turns with the hoist drum 14. A manually operable rheostat 29 is also employed, and the circuits and devices for controlling the operation of the fan motor will now be described. The mains or leading-in-wires +, - are connected with a main switch 13. The contact α of this switch is connected by a conductor a with one terminal of the 60 manually operable rheostat 29, and the other terminal of this rheostat is connected by conductors a^1 and a^2 with one end of a fixed resistance b —the other end of said resistance being connected with one end of the 65 series of resistance elements of the automatic rheostat 24. The movable arm 26 of this rheostat is connected by a conductor c with one of the commutator brushes 5^e of the fan motor 5^b, and the other commutator brush 5^e of this motor is connected by a conductor c^1 with the contact γ of the main switch. The 70 field coils of the fan motor (indicated at d) are included in a shunt circuit with lamps 75 d^1 included in parallel in said shunt circuit. The shunt circuit may be traced from the conductor a , by a conductor e to the parallel circuits of the lamps d^1 and from said parallel circuits, by a conductor e^1 to one terminal of the field coils d , the other terminal of the latter being connected by a conductor e^2 with the conductor c^1 .

The conductor a^1 is connected by a conductor f with the movable member of a manually operable high speed switch g , and the 80 stationary contact of this switch is connected by a conductor g^1 with a resistance element of the automatic rheostat 24, which is intermediate the ends of the series of resistance elements of this rheostat.

It will be apparent that under normal conditions, when the high speed switch is open, both rheostats will be included in se- 95

ries with the armature of the fan motor, and that when the high speed switch g is closed, the fixed resistance b and a portion of the resistance elements of the automatic rheostat will be short-circuited.

It will be seen that when the hoist drum 14 is rotated, the arm 26 of the automatic rheostat 24 will be moved simultaneously through the gearing described, the ratio of speeds being so arranged that the arm of the rheostat will travel slightly over one half a revolution during the drawing of one cylinder.

As previously explained, the small fan 5^a carried by the cage 5 and driven by an electric motor 5^b, supplies the air to the interior of the cylinder. Experience has demonstrated that after the cap of the cylinder has been formed, a gradual increase in the pressure of air is required to keep the cylinder properly distended as the draw progresses. It is evident that any increase in the electric current furnished the fan motor will increase the speed of rotation of the motor, thus increasing the volume and pressure of air supplied to the cylinder being drawn, hence it will be seen that by supplying the current to the fan motor through the automatic rheostat 24, which cuts out the resistance progressively as the drum 14 winds up the hoist cable, the amount of current so supplied to the fan motor will be controlled by the hoist drum and gradually increased by the rotation of the latter. The manually operated rheostat 29 in the operator's pulpit is necessary for two reasons. It has been found that in forming the neck and cap of the cylinder, more air is required than at any other stage of the draw. By cutting out more or less, or all if necessary, of the resistance in the manually operated rheostat, sufficient voltage will pass through the automatic rheostat to the fan motor to operate the fan at a speed sufficient to supply air at the pressure required to form the neck and cap. The same result can be accomplished by closing the high speed switch g so that (the fixed resistance d and a portion of the resistance of the rheostat 24 will be short-circuited.) The high speed switch, which is located in the operator's pulpit is normally open and is only closed momentarily when extra volume or pressure of air is needed and is not as a rule kept closed for any appreciable length of time. At times when the surface glass is cool, all the voltage obtainable may be required for the neck and cap, and during the draw when the operator sees that the meniscus is thickening or drawing in, additional air may be required and this can be supplied by closing the high speed switch. When however the glass is normal and other conditions are correct, the high speed switch will be open

so that the fan motor will be included in 65 series with both rheostats and the fixed resistance.

If the surface glass from which the cylinder is drawn could be maintained at a regular and uniform temperature and in the 70 same condition, the automatic rheostat would be sufficient to control the supply of the proper amount of air to the cylinder. But this is impossible, hence when the glass is stiff, more of the resistance can be cut 75 out of the hand operated rheostat thus starting the automatic rheostat with a higher initial voltage. If on the other hand the glass be soft, not so much air would be required and the initial voltage through the 80 automatic rheostat could be reduced by increasing the resistance to the current in its passage through the hand operated rheostat.

Having fully described my invention what I claim as new and desire to secure by Letters-Patent, is:—

1. The combination with hoisting means, a fan and an electric motor for the fan, of an electric circuit including said motor, a rheostat operable automatically by the hoisting means, a manually operable rheostat, said rheostats being included in series in the motor circuit, and a switch for excluding a portion of the resistance elements of one of said rheostats from the motor circuit. 95

2. The combination with hoisting means for the bait, a fan for supplying air to the cylinder being drawn, and an electric motor for said fan, of an electric circuit including said motor, a rheostat operable automatically by the hoist means, a manually operable rheostat, means for including both rheostats in series with each other and with said motor, and a switch for short circuiting a portion of the resistance elements of the 105 automatically operable rheostat.

3. The combination with hoisting means for the bait, a fan for supplying air to the cylinder being drawn, and an electric motor for said fan, of an electric circuit including 110 said motor, a rheostat operable automatically by the hoist means, a manually operable rheostat, means for including both rheostats in series with each other and with said motor, a circuit short-circuiting a portion of the resistance of the automatically controlled rheostat, a switch in said circuit, and a fixed resistance in series with both rheostats and the motor. 115

4. The combination with hoisting means 120 for the bait, a fan for supplying air to the cylinder being drawn, and an electric motor for the fan, of an electric circuit including the armature of the motor, an automatically operated rheostat, a manually operated 125 rheostat and a fixed resistance included in said circuit in series with each other and with the armature of the motor, a shunt cir-

cuit including the field coils of the motor, fixed resistance in said shunt circuit, a short circuit around the first-mentioned fixed resistance and a portion of the resistance elements of the automatically operated rheostat, and a manually operable switch in said short circuit.

In testimony whereof I have signed this specification in the presence of two subscribing witnesses.

LAURENCE EDWIN STEWART.
